(57) **CLAIM**

The ornamental design for a three dimensional panel, as
shown and described.

DESCRIPTION

FIG. 1 is a top view of a three dimensional panel showing my
new design;

FIG. 2 is a bottom view thereof;

FIG. 3 is a right view thereof;

FIG. 4 is a left view thereof;

FIG. 5 is a rear side view thereof; and,

FIG. 6 is a front side view thereof.

The three dimensional panel can be used a wall panel as well
as sound insulation. The instant ornamental design can also
be applied to other decorative goods.
